UNITED STATES PATENT OFFICE.

RICHARD CORNELIUS ELLIOTT, OF LONDON, ENGLAND, ASSIGNOR TO LANSTON MONO-TYPE MACHINE COMPANY, OF PHILADELPHIA, PENNSYLVANIA, A CORPORATION OF VIRGINIA. AUTOMATIC TYPE-CASTING MACHINE.

1,283,708.

Specification of Letters Patent.

Patented Nov. 5, 1918.

Application filed April 10, 1917. Serial No. 160,959.

To all whom it may concern:

Be it known that I, RICHARD CORNELIUS ELLIOTT, a subject of the King of Great Britain, residing at #35 Brunswick Square, 5 London, W., England, have invented certain new and useful Improvements in Automatic Type-Casting Machines; and I do hereby declare the following to be a full, clear, and exact description of the same, reference being had to the accompanying drawings, forming part of the specification, and 10 to the characters of reference marked thereon.

This invention relates to automatic type-casting machines wherein the operations of the machine, particularly the operation of the parts concerned with the relative positioning of the matrix and the mold, are controlled by a record-strip, pattern, or controller, which is generally composed or prepared in a separate machine, and in which the signals are usually but not exclusively in the form of perforations. In these automatic type-casting machines, an example of 20 which is to be found in the patent to John Sellers Bancroft, No. 625,998, dated May 30th, 1899, the matrix or die case is positioned over the mold by transposing and positioning mechanisms controlled from the 25 record-strip or pattern in which each character, symbol, space or the like, to be cast, is represented by a signal comprising in general one or more components. This record-strip or pattern is fed through the 30 interpreting mechanism of the machine intermittently or between castings, and each signal represents a single character or casting only. It is often desirable or necessary to produce successive castings from the same 35 matrix, as, for example, in quadding out a line of composition or in producing leaders, but although the same character or matrix or the equivalent thereof is to be used successively, it has hitherto been necessary that 40 each separate casting be represented in the record-strip or pattern by a separate signal; therefore, although the same matrix is to be used twice or oftener in succession, in machines as hitherto constructed the record- 45 strip-controlling parts go through the same cycle and move the strip as if an entirely 50 different matrix was to be used for the next cast.

It has hitherto been proposed, in order to

save time in composition, to provide on the 55 pattern composing or keyboard machine a repeat mechanism whereby, when it is desired that a number of casts be successively produced from a particular matrix, the compositor starts the repeat device by which the 60 designating signal is automatically repeated in the pattern without requiring that the compositor operate successively the key for producing this signal. While that arrangement saves the time of the compositor, in so 65 far as the automatic repeat mechanism will operate more quickly than the operator's fingers, it does not save anything as regards the quantity of material required for the 70 record-strip, nor does it save any wear in the keyboard or casting machines.

The chief object of the present invention is to provide in an automatic type-casting machine a repeat casting mechanism controlled by the record-strip or pattern whereby a single signal in the record-strip will 75 control or effect the production of a successive series or a predetermined number of casts from the same matrix.

According to the present invention, the 80 repeat mechanism which is controlled by a special signal in the record-strip, operates to interrupt or suspend the feed of the strip for a predetermined number of cycles of the machine, and permits the feed to be resumed after the desired number of casts has been made from the selected matrix. This suspension of the feed has the result that 85 while the matrix carrier remains in the position to center over the mold the matrix, 90 the signal for which is presented concurrently with the repeat signal, the casting, mold, dimensioning and type delivery mechanisms pursue their usual functions.

Thus one signal represents a series of 95 casts, say 5, 10, 15, 20 or other predetermined number, as against separate signals for each cast as hitherto, and saves in each case a corresponding amount of material in the record-strip. It also saves wear in the 100 machine together with a considerable saving in some cases of time at the record-strip composing machine, and the avoidance of wear to the parts such as takes place when such machine is fitted with a repeat signal 105 mechanism.

In accordance with the present invention there is provided a locking device for the

- record-strip feed mechanism, which locking device is furnished with a driving or operating mechanism receiving motion from some convenient member of the machine, 5 and an interponent or controlling member controlled from the record-strip to render the driving member of the locking device operative or inoperative on the record-strip feed as required.
- 10 It is not considered necessary to give here any details of the mechanism of the keyboard composing machine for producing the repeat signal; such machines are well known and an example thereof is disclosed in the 15 patent to John Sellers Bancroft and Mauritz C. Indahl, No. 944,405, dated December 28th, 1909. An additional or special signal-producing element or punch can be fitted on the machine, or in order that existing machines may be readily adapted to produce the required signal the repeat signal can be composed of two signal components which together have not hitherto represented any symbol or the like but either of which can 20 be or has been hitherto used in conjunction with other components for a character or like signal. The mechanism of the present invention is so contrived that when two existing components are employed the presentation in the casting machine of either component separately or in conjunction with a component not concerned with the present invention, will not operate on the mechanism for interrupting the record strip feed 25 on the casting machine, such mechanism being only operative when the two components are presented together.
- In the best known commercial machines, the signals in the record-strip are usually 30 perforations which act in conjunction with air conduits of a pneumatic system to operate the die case or matrix positioning mechanism of the casting machine. The record-strip is fed through the machine intermittently by mechanism operated in timed relation with the casting mechanism. The mechanism for feeding the strip generally comprises a ratchet and pawl mechanism 35 which rotates pin wheels adapted to engage feed holes in the margins of the record-strip, and the shaft of these pin wheels is rotated step by step to present the perforations of the successive signals to a series of air conduits by which the die-case positioning 40 mechanisms are controlled. The driving pawl of the feed mechanism is operated in timed relation to the casting, and between the pawl and the driving mechanism there is interposed a yielding coupling so as to avoid 45 damage to the mechanism should the operation of the feed mechanism be interfered with.

In carrying out the present invention as applied to an automatic type casting machine as above described, there is mounted

contiguous to the record-strip driving mechanism, a pawl and ratchet driven notched disk or cam member adapted to operate upon an arm which, when so operated upon, engages and holds the strip-feed ratchet 70 wheel; and the driving pawl for the disk is only rendered operative to effect the rotation of the disk the required degree by the repeat signal which acts upon a pawl-positioning member or motor.

Referring to the accompanying drawings: Figure 1 is a side elevation of a casting machine embodying the present invention.

Fig. 2 is a side elevation of part of the record-strip feeding mechanism of such casting machine and more particularly showing the present invention.

Fig. 3 is a view similar to Fig. 2 showing the parts in a different position.

Fig. 4 is a sectional end elevation of Fig. 2 and

Figs. 5 and 6 are detail views.

The mechanism illustrated with which the present invention is shown embodied corresponds in general with that set forth in 90 the patent to John Sellers Bancroft, No. 625,998 previously mentioned, and particularly as to the paper feeding mechanism to the improvements thereon shown for example, in the patents to John Sellers Bancroft, 95 No. 674,362 dated May 21st, 1901, and No. 700,289, dated May 20th, 1902, to which patents reference can be had for a detailed description of the mechanism and its operation. It is sufficient for present purposes to 100 point out some of the parts of the casting machine for identification purposes and to refer to the parts cooperating and co-acting with the mechanism which is more particularly a part of the present invention. For 105 example, in the casting machine shown in Fig. 1 it will be sufficient to call attention to the metal pot 7 supported by the frame 8 capable of being swung on the pivot screw 9 and of being elevated (as shown) or depressed by rotating the said screw 9 by means of the handle 10; to the flexible gas conduits 11 for leading gas to the burners under the pot 7 and to the chimney 12 for conducting off the products of combustion 110 of the gas; to the pump operating levers 13, the pump piston spring 14, the pump body spring 15, the mold 16, the mold blade operating rod 17, the matrix carrier 18, the die case positioning mechanism represented 115 by the jaw or tong 17¹, the bridge 19 and the centering pin micrometer adjustment screws 20, the centering pin lever 21, the record strip 22 and the feeding mechanism frame 22¹, parts of which feeding mechanism are more particularly shown in Figs. 2, 3 and 4. It will, of course, be understood by one skilled in the art that the various mechanisms of the machine set forth co-operate to 120 produce cast type, in accordance with the 130

signals recorded in the perforated strip, which strip is ordinarily fed along intermittently and presents a new or a repeated signal for each casting. The present invention 5 contemplates mechanism for rendering the feed mechanism inactive, whereby one signal is held presented while the other mechanisms continue to operate and thus cast repeatedly the particular type represented by 10 the signal. The means for causing such temporary suspension of the feed under control of a signal will now be described.

The usual toothed wheel 23 of the paper feed device is mounted upon the shaft 24 of 15 the feed pin wheels 25. The driving pawl 26 is mounted on a ring 27 which receives an oscillating motion from a rocking arm 28 through links 29 and 30 and a resilient coupling 31. A holding pawl 32 for the wheel 20 23 is operated through the link 30. The interpreting mechanism including the air bar 33 for the record strip is provided with 25 a series of air ducts or conduits leading to gages for the die case positioning mechanism, and between which ducts and an air supply bar or chamber the record strip 22 passes.

In embodying the present invention in a machine such as above referred to, advantage is taken of the holding pawl 32, which 30 is employed to act as the feed locking member proper, under the control of the mechanism of the present invention. In passing it is to be noted that in commercial machines such as referred to, this holding pawl has been employed under certain conditions to lock the paper feed; when sorts or single 35 types have been cast and when the machine is not controlled by a record strip representing a piece of composition, it has been usual to place in the interpreting mechanism a piece of material perforated for a single signal so that the die holder will be maintained in accurate position by the positioning mechanism. In such cases the record-strip feed 40 is not required, and a hand operated lever (see Patent 674362 above referred to) has been provided to retain the pawl 32 in engagement with the wheel 23.

50 In accordance with the present invention the pawl 32 which is pivoted at 34, as hitherto, acts normally as a holding pawl between the feed strokes of the pawl 26 until the repeat signal is presented.

55 Mounted upon an extension 35 or arm of the frame 36 is a notched disk or cam 37 which may have four notches 38 as shown in Fig. 2, or one notch as shown in Fig. 5, or two as shown in Fig. 6, in accordance 60 with the predetermined number of casts which each repeat signal is intended to denote. When one or other of the notches 37 is over a projection 39 on the pawl 32 the latter is free to respond normally to the 65 action of its driving mechanism 30, 31, but

when the normal surface of the disk 37 is over the projection 39 the pawl 32, as will be seen in Fig. 2, is locked in engagement with the wheel 23, and its driving mechanism operates without moving the pawl, and such 70 action is permitted by the resilient coupling or spring box 31.

Mounted on the shaft 40 of the disk 37 is a ratchet wheel 41 which is arranged to be rotated by a pawl 42 pivotally carried on 75 one end of a lever 43 which is loosely mounted on the shaft 40.

The other end of the lever 43 is connected by a link 44 with the rocking arm 28 from which it receives motion to operate the pawl 80 42 to rotate step by step the disk 37.

When the machine is casting ordinary composition and the repeat signal has not been presented, the disk 37 is in the position shown in Fig. 3, with a notch 38, over the 85 pawl 32 and mechanism is provided by which the driving pawl 42 for the wheel 41 is prevented from engaging the teeth of the wheel so that the disk 37 is stationary. Conveniently this mechanism comprises a 90 bell crank lever 45 pivotally mounted at 46 on the lever 43 and having one end engaging one end of the pawl 42 or a shoulder thereon. Beneath this pawl engaging arm of the lever 45 is a stop 47 carried by the 95 machine frame and adapted to engage the arm and disengage the pawl 42 from the wheel 41. The lever 45 is so mounted that it remains in the position it is placed in by the stop 47 until acted upon by another member which will be the interponent or operating member controlled by the repeat signal. 100

Thus, during normal composition, the 105 pawls 26 and 32 control through the driving mechanism 28, 31, 29, 30 the feed of the strip, and although the members 44 and 43 are being operated to rotate the wheel 41 this is rendered ineffective on the wheel by reason of the action of the stop 47 on the 110 pawl engaging lever 45.

For rendering the repeat signal operative on the mechanism 37, 45 mechanism is provided in accordance with this invention for moving the lever 45 from the position in which it is placed by the stop 47 into a position in which it will turn the pawl so that it 115 will engage and drive the wheel 41.

In the present embodiment of the invention, the interponent 48 which acts upon the lever 45 is controlled by a repeat signal 120 consisting of two existing components which if presented singly or either of them in company with another component will not operate the interponent 48, as the mechanism is so contrived that it requires the simultaneous presentation of the two components of the repeat signal to operate the interponent 48. 125

The interponent 48 is connected to a piston 49 located in a cylinder 50, one end of 130

which, through a conduit 51, communicates with a valve chamber 52 in which there is a valve opening 53 normally closed by a valve 54. Beyond the valve chamber is a chamber 55 in which is located a piston 56 the rod of which projects through the wall between chambers 52 and 55 and is connected to the valve 54. The interponent 48 is returned and piston 49 is held normally against the inner end of the cylinder by a spring 57, and the valve 54 is normally held against its seat by a spring 58.

Leading into the valve chamber is a conduit 59, the air supply to which is controlled at the air bar 33 by one component of the repeat signal, and leading into the chamber 55 behind the piston 56, is a conduit 60 the air supply to which is controlled at the air bar 33 by the other component of the repeat signal.

When the two components of the repeat signal are presented, air passing through the conduit 60 moves the piston 56 forward, and the valve 54 is moved from its seating. At the same time air enters the valve chamber 52 by the conduit 59, and passing through the valve opening travels through conduit 51 in to the cylinder 50, pushing the piston 49 and with it the interponent 48 outward.

The interponent 48 is moved to its outer position each time the signal is repeated and strikes the free arm of the bell crank when the latter reaches the end of its upward stroke which is the idle stroke of the pawl 42 so that the bell crank 45 is rocked by the member 48 to move the pawl into position to engage the teeth of the wheel 41. The upper dotted line position of the lever 45 and pawl 42, as shown in Fig. 2 is the same relatively to the lever 43 as the position shown in full lines. An advance of the interponent 48 when the parts are in the dotted position causes the tilting of the lever 45 and the engagement of the pawl 42 with the teeth of the wheel 41, this engagement continuing until the lever 45 strikes against the adjustable stop 47.

The wheel 41 is provided with twenty teeth, and when driven by the pawl 42 is moved the distance of one tooth at each operation, and each complete stroke of the arm 28 represents a casting.

In the example shown in Fig. 2 the disk 37 has four notches so that each presentation of the repeat signal effects the arrest of the record-strip for five castings.

On the first stroke of the arm 43 after the repeat signal has been presented, the disk 30 will be turned the distance of one tooth of the wheel 41 which will bring the shoulder of the notch into contact with the projection 39 of the holding pawl 32, and this pawl will be locked until, by the step by step movement of the wheel 41, the next notch

in the disk 37 comes over the projection 39 which will be when five casts have been made from a particular matrix, the signal for the positioning of which was presented by the record-strip simultaneously with the repeat signal. Should the next signal presented be a repeat signal the cycle above described will be repeated. When the repeat signal is withdrawn the piston 49 and interponent 48 are returned by the spring 57 and air is allowed to escape from the cylinder 50 by the conduits 51 and 61.

With a disk having four notches five successive casts can be represented by one signal. Should a greater number of casts than five be desired from one signal, a disk having a different number of notches may be employed; for example, with the disk with two notches shown in Fig. 6 ten casts will be represented by one signal, and with a disk having one notch shown in Fig. 5, one signal will produce twenty casts.

In order to facilitate the changing of these disks there are mounted upon the face of the wheel 41 two pins 62 which pass through openings in the disk and support it, and a ring 63 is placed in front of the disk and the whole detachably secured by a nut 64.

Should the repeat signal comprise or consist of a special perforation which is not employed alone or in combination with others to represent a character, etc., then the interponent would be projected by the air from the conduit controlled by that perforation, and this conduit could open into the cylinder behind the piston 49, the valve 54 and piston 56 being unnecessary.

I claim:

1. In an automatic type casting machine comprising mechanism for casting type from matrices in accordance with the signals of a record strip, and in combination therewith mechanism controlled by a single signal in said record strip to cause said casting mechanism to produce a plurality of castings from the same matrix.

2. In an automatic type casting machine comprising type casting devices controlled by a record strip and means for feeding said record strip, and in combination therewith record strip controlled mechanism for rendering the feeding means inoperative during a predetermined number of operations of the type casting devices.

3. In an automatic type casting machine comprising type casting devices controlled by a record strip and means for feeding said record strip, and in combination therewith mechanism, also controlled by said record strip, for rendering the feeding means inoperative during a predetermined number of operations of the type casting devices.

4. In an automatic type casting machine

comprising type casting devices controlled by a record strip and means for feeding said record strip and in combination therewith a locking device for said feeding means 5 and means controlled by said record strip and acting upon said locking device for rendering the feeding means inoperative during a predetermined number of operations of the type casting devices.

- 10 5. In an automatic type casting machine comprising type casting devices controlled by a record strip and means for feeding said record strip, and in combination therewith a locking device for said feeding 40 means, mechanism for moving said locking device into locking position and means controlled by said record strip for causing the operation of said last mentioned mechanism.
- 15 6. In a record strip feeding device comprising a pawl and ratchet mechanism and operating means therefor and in combination therewith, means controlled by said record strip for suspending the operation 50 of said mechanism during a predetermined number of operations of said operating means.
- 20 7. In an automatic type casting machine comprising type casting devices controlled

by a record strip and pawl and ratchet mechanism for feeding said record strip, and in combination therewith, a notched disk adapted to engage, between the notches thereof, with said mechanism to render the same inoperative, means for rotating said disk a step for each operation of the type casting devices, whereby the number of operative steps between the notches is a measure of the number of castings made without feeding of the record strip, and means controlled by the record strip for causing the operation of said rotating means.

35 8. In an automatic type casting machine comprising type casting devices controlled by a record strip and means for feeding said record strip, and in combination therewith, a locking device for said feeding means, comprising a notched disk, pawl and ratchet mechanism for rotating said disk, a lever operative upon the pawl, an interponent controlled by the record strip for moving said lever to cause the pawl to engage with the ratchet and a stop for causing said lever to move the pawl out of engagement with the ratchet.
